GARMENT HANGER

John G. Warmath III, Brooklyn, N.Y., assignor to Yankee Plastics, Inc., New York, N.Y., a corporation of New York

Filed Jan. 16, 1963, Ser. No. 73,203

Term of patent 14 years

(Cl. D80—8)

FIG. 1

FIG. 2

FIG. 3

FIG. 1 is a front elevational view of a garment hanger showing my new design,

FIG. 2 is a side elevational view,

FIG. 3 is an enlarged sectional view thereof taken on line 3—3 of FIG. 1,

FIG. 4 is an enlarged cross sectional view thereof taken on line 4—4 of FIG. 1, and

FIG. 5 is a rear elevational view.

This application is a continuation-in-part of my copending application, Serial Number D. 68,784 filed February 12, 1962, now Design Patent D. 194,767.

I claim:

The ornamental design for a garment hanger, substantially as shown.
